[57] CLAIM

The ornamental design for a stand for a portable telephone, as shown and described.

DESCRIPTION

FIG. 1 is a top, front and left side perspective view of a stand for a portable telephone showing our new design; FIG. 2 is a front side elevational view thereof, the rear side elevational view thereof being a mirror image of the front side elevational view thereof;

FIG. 3 is a left side elevational view thereof, the right side elevational view thereof being a mirror image of the left side elevational view thereof; and, FIG. 4 is a bottom side plan view thereof.

FIG. 1

FIG. 2

FIG. 3

FIG. 4
